(57) **CLAIM**

The ornamental design for a cover for a shade and/or flagpole, as shown and described.

DESCRIPTION

FIG. 1 is a perspective view of a cover for a shade and/or flagpole;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

The broken line and the area within the broken line shown in FIG. 7 represent unclaimed environmental subject matter.

1 Claim, 6 Drawing Sheets
